3 Claims

ABSTRACT OF THE DISCLOSURE

A curtain clasp for draping and hanging curtains in which an oblong plate has on one of its longitudinal surfaces at least one mushroom-like projection having a neck portion and a head and being adapted to slide into the undercut channel and guideway of a correspondingly shaped curtain bar. On the oblong plate's opposite surface are two spaced studs extending at right angles to said surface, one of which carries the headed end of a curtain suspending and pleating pin in an open slot arranged at right angles to the longitudinal surface of said oblong plate and extending in the direction of the second stud. The second stud contains a slot which opens upward and is parallel to the longitudinal surface of said oblong plate. This slot is adapted to receive the pointed end of the pin and hold it in locking engagement therewith by a curtain suspended from the pin.

This invention relates to a curtain clasp for draping and hanging curtains, said curtain clasp consisting of an oblong body provided with a pin adapted to be pierced through the hem of the curtain.

The object of the present invention is to provide a curtain clasp of this type which is easy and inexpensive to produce and simple and handy to use.

This object is accomplished, according to the invention, by a body which comprises a plate member which is provided at one of its longitudinal sides with at least one mushroom-like projection having a neck portion and an enlarged head portion adapted to be introduced into and slidably carried by the slot of a curtain rod, and at the other longitudinal side opposite to the first longitudinal side with two perpendicularly extending substantially cylindrical studs in spaced relation, one of which carries a pivotal pin and the other is provided with a slot extending essentially at right angles to the axial direction of the stud and adapted to receive the tip of the pin. Preferably, said oblong plate is provided at one of its longitudinal sides with two mushroom-like projections, and is made from a hard plastic such as nylon, preferably by injection molding.

The invention will be described further, by way of an example of a preferred embodiment, with reference to the accompanying drawings in which:

FIG. 1 is an enlarged scale perspective of a curtain clasp according to the invention;

FIG. 2 is a fragmentary perspective of the curtain clasp introduced into the slot of a curtain board; and

FIG. 3 is a front elevation of the curtain clasp introduced into the slot of the curtain board.

The curtain clasp shown in FIGS. 1 to 3 consists of an oblong plate member 1 having at one of its longitudinal sides two spaced mushroom-like projections 2, 3 intended to be introduced into a slot of a curtain board and comprising a neck portion 2a, 3a and an enlarged head portion 2b, 3b which is adapted to be retained slidably within the slot of the curtain board. At the other longitudinal side opposite to the first longitudinal side plate 1 carries two perpendicularly extending substantially cylindrical studs 4, 5 in spaced relation, one of which (5) carries

2

a pin 6 and the other (4) is provided with a slot 7 arranged substantially at right angles to the axial direction of the stud, in which slot the tip of the pin is engageable. Preferably, pin 6 consists of a resilient metal such as steel, and presents at one end a needlepoint and at the other a head. The pin head is held by resilient pressure within a slot 8 extending axially inwards from the end surface of stud 5 and radially outwards from the axis of stud 5 towards the axis of stud 4. Preferably, slot 8 is provided at its bottom with a small enlargement to retain the pin head in the slot. Since slot 8 is only about half as long as the diameter of stud 5, the pin 6 when pivoted forwards will be stopped approximately at right angles to the longitudinal direction of the curtain clasp.

With the curtain clasp as a handle the pin may now be pierced easily through the hem of a curtain and thereafter clasped in the slot 7 of stud 4. Thereafter the curtain clasp fastened to the curtain may be introduced into the slot of a curtain board 9 (FIG. 2).

The curtain bar, which may be made from a board or a metal profile, is provided with an inner channel 10 and a guideway 11 restricted by an upper and a lower flange 12 and 13, respectively. It will be seen from FIG. 2 that the head 2b of the projection 2 rests with an outwards facing annular surface against the inner vertical side walls of the flanges 12, 13, whereas the neck 2a of the projection 2 rests slidably with its cylindrical wall against the horizontal upper surface of the lower flange 13.

The curtain rod cut into a suitable length and provided with the desired number of curtain clasps fastened to a curtain is thereafter secured to a wall or ceiling.

Preferably, except for the pin, the curtain clasp is manufactured from a plastic, preferably a polyamide such as nylon, for instance by injection molding.

What is claimed is:

1. A curtain clasp for draping and hanging curtains from a curtain rod, said clasp comprising an oblong plate member provided on a first longitudinal side with at least one mushroom-shaped projection having a neck portion and an enlarged head portion adapted to be introduced into and slidably engaged in a slot portion of said curtain rod, and the other longitudinal side opposite to said first longitudinal side with two perpendicularly extending cylindrical studs in spaced relation, a curtain suspending and pleating pin having a head on one end and a point on the other end, one of said studs having therein an open slot arranged at right angles to the longitudinal side of said oblong plate for receiving the head of said pin therein with said pin extending toward the other stud, a slot in said other stud extending upward and substantially parallel to the longitudinal side of said oblong plate and being adapted to receive and retain the pointed portion of said pin therein.

2. The curtain clasp of claim 1 in which said oblong plate is provided at one of its longitudinal sides with two mushroom-like projections.

3. The curtain clasp of claim 1 in which the body thereof, except for the pin, is made from nylon.
